UNITED STATES PATENT OFFICE.

WILLIAM HENRY FROGGATT, OF CENTRALIA, ILLINOIS.

CAN-CLEANING MACHINE.

Application filed July 9, 1923. Serial No. 650,523.

To all whom it may concern:

Be it known that I, WILLIAM HENRY FROGGATT, a citizen of the United States, residing at Centralia, in the county of Marion 5 and State of Illinois, have invented new and useful Improvements in Can-Cleaning Machines, of which the following is a specification.

The object of this invention is to produce 10 a comparatively simple, cheaply constructed but thoroughly efficient device for cleaning the interior of cans or similar receptacles.

A further object is to produce a device of 15 this character which may be quickly and effectively clamped on the mouth of a can or other receptacle, and which includes a combined scraper and agitator mounted for both rotary and reciprocatory movement in the 20 vessel and operable by a handle arranged exteriorly of the vessel.

To the attainment of the foregoing and other objects which will present themselves as the nature of the invention is better understood, reference is to be had to the drawings which accompany and which form part 25 of this application.

In the drawings:—

Figure 1 is a side elevation showing the 30 improvement in applied position, the can or receptacle being in section.

Figure 2 is a sectional view on the line 2—2 of Figure 1.

Figure 3 is a sectional view on the line 35 3—3 of Figure 1.

Figure 4 is a sectional view on the line 4—4 of Figure 3.

Figure 5 is a top plan view of the improvement.

Figure 6 is a sectional view on the line 40 6—6 of Figure 5.

Figure 7 is a central vertical longitudinal 45 sectional view through the follower sleeve, its spring and the slotted tube, the shaft being in elevation.

In carrying out my invention, I make use of a rod in the nature of a standard 3. The bottom of the standard is headed as at 3', and has secured thereto arched springs 4' 50 that provide a resilient base for the shaft. The standard 3 is formed with continuous duplex spiral grooves 5.

The standard is surrounded by a hollow tubular shaft 4. The shaft 4 has an elongated slot 6 therethrough and has on its 55 upper end a gear 7. The gear 7 is disposed

below a head 10 secured on the top of the standard. The head 10 has a substantially U-shaped offset bracket extension 25 the outer arm of which being provided with a bearing sleeve 26 for a shaft 9. The shaft 9 also finds a bearing in a boss 27 on one side of the head 10. The shaft has keyed thereon a pinion 8 which is in mesh with the pinion 7. The shaft has a crank handle indicated by 60 the numeral 11.

Surrounding the tubular shaft 4, and in contact with the hub of the pinion 7 there is a collar 27'. Preferably the hollow shaft 4 has a flange 28 to engage the under face of 65 the collar 27'. The collar has secured thereon arched spring arms 12. The arms have their free ends rounded upon themselves to provide jaws 13 which grippingly engage the beaded mouth 2 of the receptacle 1.

Arranged for both reciprocatory and rotary movement on the shaft 5 there is a follower sleeve 14. The sleeve has a pin 15 that passes through the slot 6 in the hollow shaft 4 and is received in the spiral grooves 5 in 70 the standard 3. The sleeve 14 has downwardly arched arms 15' which are pivoted, as at 75 17, to the outwardly rounded arms 18 of the bottle cleaner fingers 19. The fingers depend from the arms and may be integrally formed therewith.

The arms 18, inward of their pivots have angle extensions 16 which are pivoted, as at 29 to ears 30 formed on a ring member 31 that surrounds the sleeve 14. Also surrounding the sleeve 14 there is a helical spring 20 that has one end contacting the arms 15' and its other end contacting the ring member 31. By this means the ring member 31 is moved downwardly on the 80 sleeve to swing the arms 18 to force the wiping and scraping fingers 19 thereof against the inner wall of the receptacle.

The operation will, it is thought, be apparent. The handle 11 is turned to revolve 100 the shaft 9 which, through the medium of its gear 8 meshing with the gear 7 will turn the hollow shaft 4, the standard 3 being held stationary. The turning of the shaft through the medium of the pin 15 in the duplex groove 5 of the stationary standard 3 imparts both a rotary and reciprocatory movement to the sleeve 14, and consequently to the wiping and scraping fingers 19 so that the utensil will be effectively cleaned in an 105 easy and expeditious manner.

The device may be readily removed from

the neck of the utensil as the arms 18 will swing toward each other when in contact with the wall of the said neck, and the spring elements 4' providing the foot of the device will likewise yield inwardly. The elements 4' and the arms 18 are also arranged in these positions when the device is inserted through the neck of the receptacle.

Having described the invention, I claim:—

10 A combined scraper and agitator for receptacles, comprising a standard having duplex spiral grooves, a headed outer end, and arched spring feet secured thereto to rest on the bottom of a receptacle, a longitudinally slotted hollow shaft surrounding the standard, a sleeve surrounding the shaft, said sleeve having a pin passing through the slot of the shaft and entering the groove of the standard, arms on the sleeve, other 15 arms pivotally secured thereto, fingers on 20

the outer ends of the last mentioned arms, a ring member slideable on the sleeve pivotally connected to the last mentioned arms beyond their pivotal connection with the first mentioned arms, a helical spring supported 25 on the sleeve and bearing against the ring member for spreading the last mentioned arms to bring the fingers thereof to wiping engagement with the inner wall of the receptacle, a gear on the outer end of the hollow shaft, a second gear supported from the outer end of the standard in mesh with said gear, an operating handle for said last mentioned gear, and curved spring arms having jaw ends to engage the mouth of the receptacle supported on but not revoluble with the hollow shaft.

In testimony whereof I affix my signature.

WILLIAM HENRY FROGGATT.
